COMBINED EYEGLASS TEMPLE AND HEARING AID CASING

Logan W. Johnson and John F. Rose, Minneapolis, Minn., assignors to The Maico Company, Incorporated, Minneapolis, Minn., a corporation of Minnesota

Application March 5, 1956, Serial No. 40,446

Term of patent 7 years

(Cl. D57—1)

Fig. 1 is a view in top plan of a combined eyeglass temple and hearing aid casing showing our new design;

Fig. 2 is a perspective view of one side thereof;

Fig. 3 is a view in elevation of the opposite side thereof; and

Fig. 4 is an enlarged transverse sectional view taken on the line 4—4 of Fig. 3.

We claim:

The ornamental design for a combined eyeglass temple and hearing aid casing, as shown.
